(57) CLAIM

The ornamental design for a pair of sandals, as shown and described.

DESCRIPTION

1. Pair of sandals

FIG. 1.1 is a perspective view of the pair of sandals, with the opposite sandal removed from the view for clarity of disclosure;

FIG. 1.2 is a left view thereof;

FIG. 1.3 is a right view thereof;

FIG. 1.4 is a front view of the pair of sandals, showing my design;

FIG. 1.5 is a rear view thereof;

FIG. 1.6 is a top view thereof.

Pair of sandals with removable toe-drying system.
